MAGNETIC DRIVE AGITATOR

George Joseph Okulitch and Igor Zozulin,
Vancouver, British Columbia, Canada

Application October 24, 1949, Serial No. 123,176

4 Claims. (Cl. 172—284)

1

Our invention relates to improvements in magnetic drive agitators.

The objects of the invention are to provide an agitator capable of being driven inside a tank or vessel from a source of power outside said vessel wherein no mechanical connection is made between the source of power and the agitator; to provide means whereby every part of the agitating element within the vessel may be removed for cleaning and sterilizing with ease and dispatch; to provide a thin diaphragm in the wall of the vessel for supporting the agitating assembly whereby the drive between the driving element and the agitating assembly is magnetic so that the magnets of one of said parts and the magnetic material attracted by said magnets may be set in close proximity to each other to the end that the magnetic attractive force may be utilized to an optimum degree.

A further object is to provide means whereby an overload on the agitator will withdraw the driving element from operating position.

A still further object is to provide means whereby the agitator cannot be rotated through its magnetic drive until the drive rotor is reset by manual means.

Other objects will appear as the specification proceeds.

Referring to the drawings:

Figure 1 indicates a longitudinal sectional view of the invention mounted upon a wall of a vessel.

Figure 2 is a diagrammatic view of an electrical circuit.

In the drawings like characters of reference indicate corresponding parts in each figure.

The numeral 1 indicates generally a tank or vessel for fluid to be agitated by the invention, and 2 is an end wall upon which the device is carried. For the purposes of description "inner end" when applied to a horizontal part will indicate that portion projecting towards the interior of the tank, or to the left of Figure 1, and "outer end" will indicate that portion projecting to the right of the figure.

An annular flange 4 is fitted into an appropriate opening formed in the wall 2 of the tank which is adapted to support a removable housing 5.

A thin diaphragm 7 is secured to the inner face of the flange 4 which is apertured concentrically to receive the shoulder 8 of the agitator shaft 9. A washer 10 is used as a stiffener for the inner portion of the diaphragm 7 and is secured thereto by a weld line about its periphery. This washer also serves to support the shaft 9.

2

The space between the outer periphery of the washer 10 and the inner periphery of the annular flange 4 is of short radial length so that ample support may be given to the shaft 9 by a diaphragm which is relatively thin.

The shaft 9 is provided with a threaded shoulder 12 which is adapted to be engaged by the free end of a bushing 14 having an inturned end 15 for the purpose of retaining a thrust bearing ball 16.

Freely mounted upon the bushing 14 of the shaft 9 is a sleeve 17 having an end closure 18 which normally bears against the ball 16. The end closure 18 is apertured as at 20 and lubrication grooves 21 as indicated in dotted line lead from the apertures 20 to discharge adjacent the diaphragm 7. An apertured disc 22 supports a rim 23 in which is embedded a plurality of permanent magnets 24 to form a driven rotor 25. The inner end of the sleeve is provided with an impeller or agitator 27 of an appropriate type, which is adapted to exert a thrust to the liquid within the tank away from the diaphragm 7 so that the rotor sleeve 17 remains in place upon the bushing 14 without requiring any fastening means.

A shaft member 30 consisting of a circular boss 31 having a flange 32 at its inner end and a drive rotor shaft 34 is aligned with the shaft 9 and is connected to the threaded end 36 of the agitator shaft 9.

A bushing 38 is fitted upon the drive rotor shaft and fitted upon said bushing is the hub 39 of a drive rotor 40, the bushing being preferably a press fit in the hub to enable the hub and bushing to slide endwise of the shaft 34.

The hub 39 is provided with an apertured disc 42 having a hollow rim 43 in which a plurality of permanent horseshoe magnets 44 are inserted.

By virtue of the drive and driven rotors their journalling shafts and mountings being carried by a thin membrane or diaphragm 7, the magnets 24 and 44 can be set with their poles very closely spaced apart, consequently the effective work done by the magnets 44 in moving the magnets 24 about their orbit is high.

The rotor hub 39 is provided with a thrust bearing 46 and interposed between the inner end of the hub and the flange 32 of the shaft member 30 is a compression spring 47 which is of sufficient strength to force the drive rotor outwardly or to the right when the several magnets 44 of the drive rotor become disaligned from the coacting magnets 24 of the driven rotor 25 for a substantial interval of time, as for instance, if an overload develops on the driven rotor so that

each magnet of the drive rotor reaches a position where its poles are directly opposite like poles of corresponding magnets of the driven rotor, then the repulsion of the said magnets 44 and 24, plus the force of the spring 47, will force the drive rotor 40 away from the diaphragm, so that no magnetic drive will then be imparted to the driven rotor 25.

The drive rotor shaft 34 extends through the end wall 49 of the housing 5 and is externally threaded as at 50.

Nuts 51 and 52 are fitted upon the shaft 34 inside and outside of the wall 49 respectively and are so adjusted as to support the centre of the diaphragm 7 and maintain the pole pieces of the magnets of the drive and driven rotors 40 and 25 equidistant from adjacent annulus of said diaphragm. By adjustably supporting the diaphragm as above described, free running of the rotors is assured and a minimum spacing between drive and driven rotor magnets may be maintained and diaphragm deflection incidental to thrust of the agitator and static head of fluid in the tank is entirely prevented.

A threaded end of the shaft 34 is bored to receive a plunger 54 which is provided with a hand knob 55 at its outer end and a cross pin 56 adjacent its inner end which extends through opposed slots 57 formed in said shaft. The plunger 54 is normally held in outwardly extended position by means of a compression spring 59 housed within the shaft and the cross pin is adapted to engage the end of the rotor 40 when the plunger is thrust inwardly to restore the magnets 44 into effective attractive position relative to the magnets 24.

A gear wheel 61 is fitted upon the hub 39 to rotate it from a driven pinion 62 which is secured upon a shaft 63 extending through the end wall 49 of the housing 5. This shaft is adapted to be driven from a motor 65 shown only in the diagram of Figure 2 and controlled by a circuit shown in the diagram of Figure 2.

A switch box 70 is fitted in a wall of the housing 5 and encloses a circuit breaker C having a push button 71 extending through the box wall into the housing 5.

In the housing adjacent the switch box is a pivotally mounted arm 73 having a transverse adjusting screw 74 adapted to bear upon the button 71 when the free end 76 of the arm is moved outwardly or to the right of the Figure 1 in response to a similar movement of the drive rotor, which causes a face of the driven gear 61 to engage said arm 73.

The motor 65 used in driving the agitator is three phase and the circuit includes three main leads 80, 81, and 82, the lead 82 being the neutral wire. A triple pole or master switch 84 controls each of the leads 80, 81 and 82 simultaneously.

The circuit breaker C consists of a normally closed double pole switch 86 and a normally open single pole switch 87 coupled for simultaneous operation. The switch 86 controls the leads 80 and 82, and the switch 87 controls a red lamp 88 connected between the leads 81 and 82 beyond the master switch 84.

A second triple pole switch 90 controls the leads 83 and 82 to the motor and also a green lamp 92 connected in parallel between leads 82 and 80. A white lamp 94 is connected in series in the lead 80 beyond the circuit breaker C and a resistor 95 is also connected in series with said lead 80 beyond said circuit breaker.

A second resistor 97 is connected in series in

the lead 82 beyond the circuit breaker C. These two resistors 95 and 97 and the white lamp 94 bypass the second triple pole switch 90 when said switch is open.

The attraction between the magnets of the drive and driven rotors 40 and 25 is sufficient to keep said rotors in close proximity to the diaphragm 7 and to impart rotation to the driven rotor from the drive rotor when the driven rotor is under normal load, but is insufficient to overcome the counter thrust of the spring 47 if there is extensive lag in rotation of the driven rotor 25 over that of the drive rotor 40.

If the rotor 40 is brought to normal motor speed rapidly from rest it will overrun the driven rotor so that for a major interval of the time of rotation the magnets of one rotor will be circumferentially separated or out of step with those of the other rotor and the spring 47 will cause the rotor 40 to recede endwise of its shaft away from the diaphragm.

When both rotors are at rest, or when the drive motor is running slowly, the respective magnets can be brought in opposition to each other by thrusting the knob 55 inwardly to impart endwise movement to the rotor 40. This will enable the attraction of the magnets one to the other to be more effective, so that the drive rotor will remain in its working position in close proximity to the diaphragm 7.

The device as shown is in position to be started with the agitator 27 in place upon its shaft and the rotor 40 advanced to operating position close to the diaphragm 7 and the fluid to be agitated in the tank.

The circuit breaker C will have its switch 86 closed and its switch 87 open. To set the device in normal motion the switch 84 is closed. This permits current to flow through the leads 80, 81 and 82 to motor, but the potential through 82 is lowered by the resistor 97 and the potential through 80 is lowered by the resistor 95 and the white lamp 94, which latter will be illuminated incidental to the surge of current to the motor in overcoming its initial inertia. As this surge drops the resistor will pass the required potential and allow the white lamp to go out.

During this interval the motor will be gathering speed and the magnets of the drive rotor 40 will each be drawing a magnet of the driven rotor about its orbit so that both rotors will be rotating in unison.

As soon as the white light goes out the triple pole switch 90 is closed so that the current now flows directly through the full length of the leads 80 and 82, and also through 81 so that the motor immediately steps up to normal running speed.

Simultaneously with the closing of switch 90 the green lamp 92 is illuminated, indicating to the operator "Normal operation."

The opening of the master switch 84 will break the entire circuit and stop the motor but will not cause the driven rotor to retract from the diaphragm.

If in normal operation, an overload or other mishap causes the driven rotor to get out of step with the drive rotor, the latter will retract from driving position under the influence of spring 47, thus tripping the arm 73 and causing the switch 86 to open and the switch 87 to close, thus shutting off the motor and illuminating the red lamp 88, thus indicating that the device requires attention.

With the motor stopped manually and it being desired to dismantle the agitator for cleaning, it

is first necessary to break the magnetic attraction between the rotors. This is done by closing the second triple pole switch 90, then closing the master switch 84 momentarily, which gives full current to the motor, causing it to rotate rapidly at full current, thus throwing the drive rotor out of step with its driven rotor and allowing the spring 47 to retract the driven rotor. The above frees the driven rotor which can then be lifted off its shaft 9 for cleaning, etc.

What we claim as our invention is:

1. A device for imparting rotation to an agitator or the like comprising a drive rotor and a driven rotor mounted in axial alignment, permanent magnets regularly spaced about the periphery of one rotor and complementary pieces of magnetic material spaced about the other rotor, means for selectively rotating the drive rotor at a slow and at high speed, means for imparting endwise movement to one of the rotors to move it out of operative attraction from the other of said rotors when the rotation of said rotors is at substantial variance to each other, said endwise movement imparting means being of such magnitude as to overcome the operative attraction of the magnets when high speed rotation is imparted to a rotor while said rotor is at rest.

2. A device for imparting rotation to an agitator or the like comprising a drive rotor and a driven rotor mounted in axial alignment, permanent magnets regularly spaced about the periphery of one rotor and complementary pieces of magnetic material spaced about the other rotor, means for selectively rotating the drive rotor at a slow and at high speed, spring means for imparting endwise movement to one of the rotors to move it out of operative attraction from the other of said rotors when the rotation of said rotors is at substantial variance to each other, said spring means being of such force as to overcome the operative attraction of the magnets when high speed rotation is imparted to a rotor and said rotor is at rest, one of said rotors being endwise detachable subsequent to endwise movement of the other rotor from operative attraction position.

3. A device for imparting rotation to an agi-

- tator or the like comprising a drive rotor and a driven rotor mounted in axial alignment, permanent magnets regularly spaced about the periphery of one rotor and complementary pieces of magnetic material spaced about the other rotor, electromagnetic means for progressively rotating the drive rotor first at slow and then at high speed, and a manually controlled switch for applying said means at high speed to the drive rotor when at rest, and means operative in response to rotation of one rotor at a substantially different rate of speed of the other rotor for moving one rotor endwise out of operative attraction from the other rotor.
- 15 4. A device for imparting rotation to an agitator or the like comprising a drive rotor and a driven rotor mounted in axial alignment, permanent magnets regularly spaced about the periphery of one rotor and complementary pieces of magnetic material spaced about the other rotor, means for imparting endwise movement to one rotor to move it out of operative attraction when one rotor is rotating at a substantially greater speed than the other, manual means for returning the endwise moved rotor to operative attractive position adjacent the other rotor, means for rotating one rotor and through it drive the second rotor at a slow and a high speed, and means for imparting such high speed to one rotor as to cause endwise movement of a rotor out of operative attraction to the other rotor.
